UNITED STATES PATENT OFFICE.

CHARLES K. TILDEN, OF HALLOWELL, MAINE, AND HORATIO S. EARLE, OF DETROIT, MICHIGAN.

DESIGN FOR A GRASS-HOOK.

SPECIFICATION forming part of Design No. 32,227, dated February 13, 1900.

Application filed January 2, 1900. Serial No. 182. Term of patent 14 years.

To all whom it may concern:

Be it known that we, CHARLES K. TILDEN, residing at Hallowell, county of Kennebeck, State of Maine, and HORATIO S. EARLE, residing at Detroit, in the county of Wayne, State of Michigan, citizens of the United States, have invented and produced a new and original Design for Grass-Hooks, of which the following is a specification, reference being had to the accompanying drawings, and to the letters of reference marked thereon, which form a part of this specification.

This invention relates to a new and original design for grass-hooks.

15 In the accompanying drawings, Figure 1 is a perspective view of our design for grass-hooks. Fig. 2 is a plan view thereof. Fig. 3 is an elevation looking toward the tang of the blade.

20 The leading feature of our design consists in a curved blade tapering toward the point and having a raised flange at the back thereof and a handle attached to the tang of the blade provided with reverse bends and carrying a hand-grip which stands nearly at right angles with the blade. The handle inclines up-

wardly from the blade, so that the hand-grip thereof is above the plane of the blade's under face.

A designates the blade, and a the flange at 30 the back thereof.

B designates the handle, having the hand-grip C and the reverse bends b and c therein, and D designates the point of union between the handle and the blade, the whole presenting an ornate and harmonious figure, as shown in the drawings.

Having thus described our design, what we claim is—

The design for a grass-hook, substantially, 40 as herein shown and described.

In testimony whereof we sign this specification in the presence of witnesses.

CHARLES K. TILDEN.
HORATIO S. EARLE.
